(57) CLAIM

The ornamental design for a lid for hamper, as shown and described.

DESCRIPTION

FIG. 1 is a perspective view of my lid;

FIG. 2 is a top plan view of my lid;

FIG. 3 is a side elevational view of my lid, the other side views being the same; and,

FIG. 4 is a bottom plan view of my lid.

The surface(s) or portion(s) of the article not shown in the drawing or described in the specification form(s) no part of the claimed design.
